United States Patent Office

Des. 192,719
Patented May 1, 1962

192,719

ASHTRAY

Frank Mariani, New York, N.Y.
(90 Herbert Ave., Closter, N.J.)

Filed Mar. 30, 1961, Ser. No. 64,559

Term of patent 14 years

(Cl. D85—2)

FIG. 1

FIG. 2

FIG. 3

FIG. 4

FIG. 1 is a top perspective view of an ashtray showing my new design.

FIG. 2 is a top plan view thereof.

FIG. 3 is a side elevational view thereof.

FIG. 4 is an end elevational view thereof.

The bottom is substantially plain and unornamented. I claim:

The ornamental design for an ashtray, as shown and described.
